UNITED STATES PATENT OFFICE.

BENJAMIN HENRY BROWN, OF NEW PLYMOUTH, NEW ZEALAND.

REVERSING-GEAR FOR STEAM-ENGINES.

No. 799,712.

Specification of Letters Patent.

Patented Sept. 19, 1905.

Application filed May 13, 1905. Serial No. 260,326.

To all whom it may concern:

Be it known that I, BENJAMIN HENRY BROWN, a subject of His Majesty the King of Great Britain and Ireland, residing at Range Farm, 5 New Plymouth, in the Provincial District of Taranaki, in the Colony of New Zealand, (care of J. Brown,) have invented certain new and useful Improvements in Reversing-Gear for Steam-Engines and the Like, of which the following is a specification.

This invention relates to gear used for reversing steam-engines and the like, and according hereto the valve-rod is provided with a slotted bracket within which the crank-pin 15 of a crank-shaft and its brasses are fitted. The crank-pin carries upon its free end a block, and to the middle part of the crank-shaft a toothed reversing-wheel is fixed. The block upon the end of the crank-pin passes into a 20 gap provided in a mutilated disk, the said disk being mounted upon a short crank-shaft, which is revolved by any convenient reciprocating part of the engine. A reversing-lever is fixed upon a reversing-shaft upon which an arm is 25 fixed having a rack adapted to gear with the toothed reversing-wheel. To reverse the engine, the lever is operated to make the rack gear with and revolve the reversing-wheel which carries the crank-pins through a portion 30 of a circle, the traverse of the crank-pins being limited by the gap in the mutilated disk. The crank-pin and reversing-wheel are revolved by the crank-shaft and the mutilated disk, thereby reciprocating the valve-rod in 35 the bracket of which the crank-pin and its brasses slide.

The drawings illustrate the invention applied to a two-cylinder engine.

Figure 1 is a front elevation, partly in section, and Fig. 2 a side elevation, partly in section, of a vertical double-cylinder engine fitted with my invention. Fig. 3 is a front elevation, and Fig. 4 an end elevation, of a mutilated disk and its shaft and crank. Fig. 5 is 45 a side view of a reversing-wheel, and Fig. 6 a section on line A A of Fig. 5. Fig. 7 is an end view, and Fig. 8 a side view, of a rack and its arm. Fig. 9 is an end view of a block, and Fig. 10 an elevation of a crank-shaft fitted 50 with a reversing-wheel and blocks upon its crank-pins. Fig. 11 is a side view of a valve-rod slotted bracket. Fig. 12 is an end view of the same. Fig. 13 is an end view of the bracket carrying the crank-shaft and its connections.

Associated with each cylinder of the engine

is a valve-rod 1, which has a bracket 2, provided with a slot 3, within which a crank-pin 4 and its brasses 5 are adapted to slide. The crank-pin is provided with a block 6, shaped 60 as shown in Figs. 9 and 10 and adapted to enter a gap 7, formed in the mutilated disk 8. The crank-shaft 9 is carried in bearings 10 and 11 and has secured to it near its middle a toothed reversing-wheel 12. The mutilated disk 8 is 65 mounted upon or integral with a shaft 13, carried in a bearing 14. At the other end of the shaft 13 an arm 15, carrying a crank-pin 16, is secured.

In the arrangement shown on the drawings 70 of a two-cylinder engine two mutilated disks 8 are shown arranged with their crank-pins 16 at right angles to each other, and these crank-pins are coupled to pump-rods 17 by connecting-rods 18. The connecting-rods are 75 reciprocated by the pump-rods, and the shafts 13, with their mutilated disks 8 and blocks 6 and crank-pins 4, are revolved, and thereby operate the valve-rods 1. A reversing-shaft 19 is mounted in bearings 20 and 21 and is 80 fitted with a reversing-lever 22. An arm 23, fixed upon the end of the shaft, is provided with a rack 24, adapted to gear with the toothed reversing-wheel 12.

To reverse the engine and cause it to operate in a direction opposite to that indicated in the drawings, the reversing-lever 22 is operated to bring the rack 24 into gear with the toothed reversing-wheel 12 and to revolve the reversing-wheel until the blocks 6 rest 90 upon the opposite side of the gaps 7 of the mutilated disks 8, the number of teeth in the rack being just sufficient to carry the blocks 6 over, as described.

What I claim, and desire to secure by Letters Patent of the United States, is—

1. For the purpose indicated in combination, a valve-rod, a slotted bracket integral with the valve-rod, a crank-shaft, a crank-pin on the crank-shaft fitted with a block, a disk 100 having a gap adapted to receive the said block, a crank-shaft carrying the said disk, and means for revolving the crank-shaft, substantially as set forth.

2. For the purpose indicated in combination, a valve-rod, a slotted bracket integral with the valve-rod, a double crank-shaft, crank-pins on the crank-shaft, blocks secured to the ends of the crank-pins, disks provided with a gap adapted to receive said blocks, 110 crank-shafts upon which the disks are mounted, connecting-rods coupled at one end to the

said crank-pins, and at the other end to pump-levers of the engine, substantially as set forth.

3. For the purpose indicated in combination, a valve-rod, a slotted bracket integral with the valve-rod, a double crank-shaft, crank-pins on the crank-shaft, blocks secured to the ends of the crank-pins, disks provided with a gap adapted to receive said blocks, crank-shafts upon which the disks are mounted, connecting-rods coupled at one end to the said crank-pins, and at the other end to pump-levers of the engine, a toothed reversing-wheel secured to the shaft and means for reversing the said wheel, substantially as set forth.

4. For the purpose indicated in combination, a valve-rod, a slotted bracket integral with the valve-rod, a double crank-shaft, crank-pins on the crank-shaft, blocks secured to the ends of the crank-pins, disks provided

with a gap adapted to receive said blocks, crank-shafts upon which the disks are mounted, connecting-rods coupled at one end to the said crank-pins, and at the other end to pump-levers of the engine, a toothed reversing-wheel secured to the shaft, means for reversing the said wheel, a reversing-shaft, a reversing-lever fixed to the reversing-shaft, an arm fixed to the reversing-shaft, a rack upon the end of the arm adapted to engage with the toothed reversing-wheel, substantially as set forth. 25

In testimony whereof I have signed my name to this specification in the presence of two witnesses.

BENJAMIN HENRY BROWN.
